Patented June 15, 1926.

UNITED STATES PATENT OFFICE.

CHARLES S. MALLETT, OF TORONTO, ONTARIO, CANADA, ASSIGNOR TO GENERAL ELECTRIC COMPANY, A CORPORATION OF NEW YORK.

KEYLESS SOCKET.

Application filed December 31, 1923, Serial No. 683,625, and in Canada October 26, 1923.

My invention relates to improvements in keyless sockets and receptacles and the object of the invention is to improve their construction and also to reduce the cost of manufacturing by eliminating the operation of threading of holes, which operation is responsible for the major portion of the loss in the production of such sockets and receptacles.

10 For a consideration of what I believe to be novel and my invention, attention is directed to the accompanying description and the claims appended thereto.

In the accompanying drawing, Fig. 1 is 15 a sectional view through my improved keyless socket or receptacle; Fig. 2 is a perspective detail of the insulating base; Fig. 3 is a perspective detail of the center terminal; Fig. 4 is a perspective detail of the 20 shell terminal; Fig. 5 is a perspective detail of the screw shell, and Fig. 6 is a plan view of the insulating base.

1 indicates the metal casting of the socket or receptacle which is provided with the 25 usual insulating lining 2 and cap 3. 4 indicates an insulating base which is made of porcelain or equivalent material and is provided with a relatively deep central recess 5, the latter having a side opening 6 as shown 30 in Figs. 1 and 6 to receive one of the circuit terminals. Centrally disposed in the bottom of the base is a rivet-receiving opening. 7 indicates a metallic terminal which is connected to the center contact and comprises 35 an L-shaped strip having a rivet-receiving hole located near its inner end. The vertically-extending part 8 thereof is provided with a threaded hole 9 for the reception of a screw. The upper end of the terminal is 40 outturned as indicated at 10 so that a circuit wire may be clamped between it and a clamping screw 11.

14 is a shell terminal which comprises a strip 15, Fig. 4, provided with a screw-receiving hole near its upper end, the portion of the strip above the hole being outturned as indicated at 17 to hold one of the circuit wires between it and a clamping screw. The opposite or lower end of the 50 strip is forked to form two arms 18 and 19 between which is a V-shaped space. The extremities of the arms are upturned at 20 and 21 to form holding devices to prevent the terminal from moving from its position

after assembly. The purpose of separating 55 the arms is to avoid the rivet which unites the parts of the socket and thus electrically separate the center contact and shell parts.

22 and 23, Fig. 2, are small sockets formed in the insulating base and are adapted to 60 receive the tips 20 and 21 of arms 18 and 19 and thus firmly hold the terminal in position.

24 is a shallow recess formed in the left-hand side of the base 4 and into which the 65 vertical portion 15 of the shell terminal 14 extends. 26 is a sheet metal screw shell provided with a rectangular slot 27 extending diametrically across it and partway down the sides thereof. Formed integral with the 70 base and extending into the slot 27 is a flat-sided projection 28 which engages the walls of the slot and prevents the shell from turning on the base when a lamp or other device is screwed into the shell. 75

29 and 30 are small holes or orifices in the bottom of the shell on each side of the slot 27, which when the parts are assembled register with the small sockets 22 and 23 in the base. The arms 18 and 19 of the 80 shell terminal extend through the slot 27 and engage the under surface of the top of the shell at each side of the slot to establish electrical connection. The extremities 20 and 21 of the terminal extend upwardly 85 through the small orifices 29 and 30 into the sockets 22 and 23 in the base 4. 31 is an insulating washer or disk located within the screw shell and which engages the arms 18 and 19 and presses them firmly against the 90 under side of the top of the screw shell. 32 is a hollow rivet or eyelet provided at its lower end with a head which engages the under surface of the washer 31 and the stem thereof extends upwardly through the hole in 95 the center of the washer and between the arms 18 and 19 of the shell contact, through the center slot 27 in the shell and through the hole in the bottom of the base into the center contact terminal 7. The upper end 100 of the rivet or eyelet is flanged over this center terminal thus securing all of the parts together. The lower end of the rivet forms the center contact of the socket or receptacle and is adapted to be engaged by 105 the lamp or other device when screwed into the shell. On the base are also radial projections 35 which engage inwardly extend-

ing projections formed on the surrounding metal casing to prevent relative annular movements of these parts.

It will thus be seen that when all the parts are assembled they are held together by means of the eyelet 32 thereby dispensing with the use of screws and therefore the formation of threaded holes in numerous small parts.

10 By securing all the parts of the socket together by a single member and dispensing with the use of screws, the cost of manufacture is materially reduced and losses incident to the rejection of defective pieces 15 is decreased.

By utilizing a single piece porcelain base having a large central recess which opens at one side only, ample space is afforded to receive a tool for riveting over the edge of 20 the eyelet without danger of injuring the porcelain. The L-shaped terminal 7 is prevented from twisting on the rivet by means of the side walls of the recess. The vertically-extending part 8 of the terminal being located as it is at the mouth of the side opening, is well separated from the outer shell thereby avoiding danger of short circuits due to careless wiring.

25 The terminal 14 being on the opposite side of the vertical wall of the center recess is well insulated and is also separated from the casing by a substantial space.

What I claim as new and desire to secure 30 by Letters Patent of the United States, is,—

1. In a keyless socket or receptacle, the combination of a single piece insulating base having a relatively deep central recess which is open on one side, a screw threaded shell, the top of which is diametrically slotted, a 35 terminal member which extends through the slot and is divided at one end into arms which engage the top of the shell to establish electrical contact therewith, the ends of 40 said arms passing through the top of the shell and engaging the base, the opposite end of said member being arranged to receive a circuit wire, a terminal member which is located in the recess and extends 45 through the side opening, an insulating disk 50 inside of the shell, and a means which extends through the disk and base into the terminal in said recess and unites the shell, base and terminals.

55 2. In a keyless socket or receptacle, the combination of a single piece insulating base having a relatively deep central recess which is open on one side and a relatively shallow recess on the side opposite the opening, an L-shaped terminal member which is located 60 in the central recess and extends through its open side, a sheet metal screw shell having a slot in its top, a shell terminal member, one end of which occupies the shallow recess, the other end being forked and extending 65 through said slot and engaging the

under surface of the top of the shell, positioning means integral with the shell terminal member which extend through the top of the shell and engage the base, an insulating washer in the shell, and a rivet which extends upwardly through the washer, slot in the shell, base and L-shaped terminal and unites said parts.

3. In a keyless socket or receptacle, the combination of a single piece insulating base having a relatively deep central recess which is open on one side, a terminal member which is located in the recess and extends through the open side, a screw shell having a central slot in its upper end and also a pair of holes, an insulating washer in the shell, a terminal member for the shell having a forked lower end which is situated between the washer and the shell and has projections that enter said holes, and an eyelet which extends upwardly through the washer and slot and between the forked end of the shell terminal member into the base and first-named terminal and unites said parts.

4. In a keyless socket or receptacle, the combination of a single piece insulating base having a central side opening recess in its upper side and a pair of small sockets in its under side, a screw-threaded metal shell having a slotted top and a pair of holes which register with the sockets in the base, a washer in the shell, a terminal member which is located in the said recess, a second terminal member which extends through the slot in the shell and has a pair of arms which are situated between the washer and the shell, the ends of which project upwardly through the holes in the shell into the sockets in the base, and a rivet which 100 unites the terminals, base and shell and also forms the center contact of the socket.

5. In a keyless socket or receptacle, the combination of an insulating base having a central side opening recess in its upper side and a straight sided projection and a pair of sockets on its under side, a sheet metal screw shell having a slotted top, the side walls of which engage the projection to prevent relative movements of the parts, a center terminal member located in said recess, a shell terminal member having spaced arms which extend through the slot and engage the under side of the top of the shell, there being projections on the outer ends of the arms which extend through the top of the shell into the sockets in the base, a washer in the shell, and a rivet which extends through the washer, base and center terminal and unites the parts.

In witness whereof, I have hereunto set my hand this twenty-seventh day of December, 1923.

CHARLES S. MALLETT.
